UNITED STATES PATENT OFFICE.

GEORGE M. WHITIN, OF WHITINSVILLE, MASSACHUSETTS.

COTTON-COMBER.

1,151,143.

Specification of Letters Patent. Patented Aug. 24, 1915.

Application filed April 25, 1914. Serial No. 834,308.

To all whom it may concern:

Be it known that I, GEORGE M. WHITIN, a citizen of the United States, residing at Whitinsville, in the county of Worcester 5 and State of Massachusetts, have invented the following described Improvements in Cotton-Combers.

The invention is an improved construction of combing apparatus specially adapted for 10 producing thoroughly combed sliver with a low percentage of waste production, that is to say, the object of the invention is to reduce the percentage of good fibers thrown down as waste without sacrificing the quality 15 of the product sliver, and to attain this result with high speed and high production, but other objects are also included in the invention, and these and the principle on which the invention operates, will all become 20 apparent to those skilled in this art, in the following description and drawings and also by the claims.

In the drawings, Figure 1 is a transverse section of a part of one of the combing heads 25 of a comber, taken through the working parts of the comb cylinder and coöperating mechanism. Fig. 2 is a top plan of the parts shown in Fig. 1, adjacent to one of the intermediate frame uprights of the machine. Fig. 3 is a detailed section of Fig. 2 on line III—III. Fig. 4 is a front elevation of the parts shown in Fig. 2, broken away in places to illustrate parts in rear. Fig. 5 is an elevation of one end of the combing cylinder and detaching roll, both ends 30 of such parts being alike. Fig. 6 is a sectional view on line VI—VI of Fig. 5. Fig. 7 represents a modified form, the view being a section adjacent the end supports of the several rolls; Fig. 8 (on Sheet 3) is a perspective view of the bearing block for the 35 detaching roll used in this form of the invention; and Fig. 9 a modified form.

The drawings illustrate only those parts 40 of the comber which are directly concerned with the treatment of the cotton. The rest of the machine may be constructed in any manner suitable for operating the parts shown and according to the functions there- 45 of as hereinafter explained; it may be, for example, as shown in Patent No. 822,479, dated June 5th, 1906, or as common in the art of Heilmann combers. It will be understood that the machine comprises several 50 similar combing heads, and also a drive-head, the former being disposed in a row

with certain operating shafts running through them to the drive-head at one end by which they are operated. The combing heads are supported by a series of intermediate frame uprights such as partially shown at 1. These have upper margins which are inclined and support the bearings for the feed rolls and piecing mechanism bolted to them. The said upper margin of the upright has heretofore formed a continuous inclined plane from its upper to its lower end, but in the present case the upper portion as indicated at 2, is cut down so as to be offset or depressed with reference to the forward portion thereof, thus providing a supporting surface for the journal block 3 of the shaft of the feed roll 4, which is lower than formerly and therefore permits the shaft to operate nearer to the axis of the 70 comb cylinder. The feed-roll shaft 4 may be one of the several continuous shafts above mentioned, which are common to all the heads and driven by the drive-head. The lap of cotton supplied from the lap roll 80 on a creel-frame, not shown, moves downwardly on the lap plate 5, into the bite which this roll 4 has upon an upper feed roll 6, the latter being held in engagement therewith by means of arms 7, which are subject- 80 to spring-pressure as customary in cotton combers. In the present case the arms hold the top feed roll 6 on the forward side of the lower feed roll so that the common tangent of such rolls, at their point of contact, inclines downwardly toward the comb cylinder. The two feed rolls are thus disposed at an inclination with respect to the comb-cylinder, and they are made with sharp intermeshing flutes as indicated. The 90 forward rotation of these rolls, which may be intermittent as usual, advances the end of the lap into the jaws 8 and 9 of the nipper mechanism which open for the purpose. The lower nipper jaw 8, or so-called cushion 95 plate, is rigidly supported beneath the feed rolls and by means of parts not indicated, but which hold it in a fixed position wherein its nipping edge is close to the path of travel of the needle- and detaching half-laps of the 100 combing cylinder. The other jaw 9, or nipper-knife, is carried by nipper arms 10, operating to close the knife edgewise against the cushion plate so as to nip the fringe of cotton lap thereagainst and hold it project- 105 ing therefrom during the operation of the needle half-lap in the usual way. The nip-

110

per knife opens in time for the detachment, moving upwardly above the said common tangent of the feed rolls. The knife, in order to partake of these movements, is inclined in the same direction as the two feed rolls, and the usual top comb 11 immediately in front of the knife is similarly inclined.

The comb cylinder 13 comprises the needle half-lap 12 above mentioned and a detaching segment 15, both carried on the cylinder shaft 14 which is journaled in the frame upright 1, and driven by the drive head. Immediately following the combing of the nipped tuft, the nipper jaw 9 opens and the detaching half-lap or segment 15 thereupon engages the combed fringe or tuft, pressing it against the under side of the detaching roll 16. This roll is a leather-covered roll and coöperates with the detaching segment to draw the combed fringe from the body of the lap, held by the feed rolls 4 and 6, drawing the tail end of such tuft through the open nippers and also through the top comb 11 and forwarding or projecting it under a second roll 17, and into engagement with a third roll 18, which latter turns the tuft upwardly between itself and the second roll. The second and third rolls, 17 and 18, are piecing rolls, rotated independently of the detaching roll and out of contact therewith. The roll 18 is relatively large in proportion to the detaching roll, being formed on a shaft common to all of combing heads and driven by gearing in the drive-head which gives it an intermittent forward rotation holding it stationary, or turning it backwardly, between forward strokes, as already known in piecing motions. The shaft is journaled in pillows 20, which are adjustably mounted on the frame uprights 1 and from the supporting means of the other rolls and certain of their appurtenances as will later appear. The roll 17 is leather-covered, although this is not necessary, and is individual to each head, that is to say, it is wholly contained within the head, being removable therefrom like the detaching roll. Its end gudgeons 17^a (Fig. 3) are each incased in gudgeon sleeves 17^b which rest by a slabbed side upon the inclined surface of a bearing block 22, the latter adjustably bolted to a bracket arm 23 projecting laterally and rearwardly from the pillow block 20 above referred to. The supporting surface of the bearing block 22 is inclined downwardly toward the front of the machine so that when the gudgeon sleeves 17^b are resting thereon the working face of the roll 17 is caused to bear against the larger piecing roll 18, but does not project into the path of the segment, from which it is separated by a narrow crevice of sufficient width to allow the detached and combed tuft to pass through it. The roll 17 is urged downwardly and forwardly so as to bear firmly

against third roll 18 by pressure applied to its gudgeons by a saddle member 24 which bears on the gudgeon sleeve 17^b and also on the corresponding gudgeon sleeve 16^b of the detaching roll 16. The said saddle is permanently joined to the end of a hooked or gooseneck stirrup 25, the lower end of which is removably engaged with a stud on the weighted lever 26. This lever is pivoted at 27 beneath the cylinder 13 and weighted at its forward end by a link 28 and a weight or spring, not shown. The stirrup can be lifted against the pressure of this lever and removed, with the saddle, from pressing relation upon the rolls, whereupon both rolls may be removed. The pressure applied by this single means, to the ends of both rolls, also serves to press the detaching roll in a rearward direction, or toward the rear side of the comb cylinder, and for this purpose the detaching roll is supported or guided in open slots in the blocks 22, which slots lie at the said inclination. The sleeves 16^b on the gudgeons 16^a of the detaching roll are slabbed on both sides, parallel, and inserted in the slots being supported therein in a position in which the working surface of the roll will be engaged by the detaching segment as above described, but will escape the needles of the half-lap. When the bracket arm 23 is a fixed part of the machine, as in the present case, the detaching segment is mounted in the cylinder with its surface slightly higher than the points of the needles, and the position of the detaching roll is fixed so as to clear the latter but yet to be engaged by the segment. The means for determining this position of the roll according to the present invention comprise two elements or sets of elements, either one or both of which may be used in the same machine. In the construction illustrated by Figs. 1-6, the ends of the roll are formed or otherwise provided with bosses 31, which are cylindrical or circular in cross section and no larger in diameter than the body of the roll, preferably slightly smaller as indicated. These bosses are fixed to the body of the roll, and rest on two circular bearing surfaces 32 formed on, or rotating with the comb cylinder 13 at each end. The diameters of such circular bearing surfaces 32 and bosses 31 are proportioned to support the working face of the roll in the position above referred to, except when it is engaged and slightly lifted by the detaching segment. The slots in the blocks 22 in this case support the detaching roll in a lateral sense, as guiding means, permitting the roll to yield to the impact from the segment in an upward and forward direction, which yielding is against the pressure of the saddle. The gudgeon sleeves 16^b may not engage any surface or support to limit the

extent of their entrance into their slots when the machine is thus constructed. The frictional engagement of the bearing surfaces 32 and bosses 31 causes the latter to drive the detaching roll in a forward direction, and also at a slightly higher surface speed than the detaching segment so that the said roll is rotating when engaged by the segment and the latter is therefore relieved of the duty of overcoming its inertia. The tendency toward slipping or imperfect grip on the tuft is thereby reduced, particularly under high speeds.

It should be noted that the drawings pur-
15 posey exaggerate the proportions of the parts above described, for clearness of illustration, but it will be understood that the relative dimensions of the bosses 31 and the ring bearings 32, are intended to be so ad-
20 justed as to produce the action described with the least shock and jar, and prefer-
25 ably, though not necessarily, so as to rotate the detaching roll with a slightly higher surface speed than the segment. When the bearing surfaces 32 extend continuously
30 around the cylinder from back to front of the segment, as in Figs. 1 to 6, the detaching roll is supported wholly thereby and by the segment, being merely guided or held in position by the supporting blocks 22. Figs.
35 7-9 illustrate a construction in which the boss-driving bearings are present only im-
mediately in front of the detaching segment and the bearing blocks 22 are provided with
40 adjustable supports to withstand the saddle pressure on the roll. As shown in Fig. 9, the bearing members 42 are mounted at the ends of the cylinder, extending forwardly about 90° in front of the forward side of
45 the segment. These members are adapted to engage the roll bosses 31 in time to start the detaching roll in motion before it en-
50 gages the segment. After the segment passes the roll, it rests, by its gudgeons, on bearings formed in the bottom of the slots in the blocks 22. These bearings are each formed by the flat, enlarged end 33 of a screw 34, tapped into the block and slot, where the gudgeon sleeve 16^b may rest on
55 it, the sleeve being slabbed on a bevel for this purpose, as indicated at 35. The screw thus forms a compact and stable bottom bearing for the detaching roll, which is accessible from the rear of the machine for
60 adjustment. It will be evident that it would be equally useful for supporting the detaching roll during the whole interval between detachments. By the adjustment of the screw, the roll can be set so that the bearing members 42 will engage the bosses with the least jar, the forward ends of said bearing members, and also the forward edge of the detaching segment being beveled for the same purpose.

65 The fluted clearer roll 19 is held as usual

in the horsetails 29, the latter being pivoted on the horsetail supports 30, bolted to the pillow-block 20 above referred to. This clearer roll rests by its own weight and the weight of its horsetails upon the fluted 70 piecing roll 18 and directs the combed and pieced tufts into the usual sliver pan or other means by which it is condensed and delivered from the machine.

The saddle 24 which spans the adjacent 75 gudgeon sleeves 17^b and 16^b is pivotally connected to the end of the stirrup 25, and formed with a downward extension, or leg, on its front side which is concaved to fit the gudgeon sleeve of roll 17. The rear end is 80 flat where it rests on the gudgeon sleeve of roll 16 and the relation of its pivotal joint and the two gudgeon bearings is such that the pressure is divided about equally between such gudgeons and notwithstanding 85 that the detaching roll yields forwardly while the piecing roll 17 yields rearwardly. Obviously the said saddle could be formed otherwise to produce the same effect. The engagement of its concave bearing upon the 90 gudgeon sleeve 17^b permits it to be rocked forwardly thereon, as indicated by the dotted line position in Fig. 7. When in this position the pressure is relieved from the detaching roll and the bearing block slot is 95 opened so that that roll can be removed without relieving all the pressure on the forward roll, or unhooking the stirrup from its stud on the weight-lever, this being a feature of convenience as a time saver, 100 since detaching rolls require frequent attention. By pushing on the stirrups the saddles are readily replaced in normal position.

In order to vary the pressure applied by the common weighting means to the two 105 rolls 16 and 17, the direction of pull on the stirrup is shifted forwardly or backwardly, as desired, and this is preferably accomplished by the means shown in the drawings (Fig. 7). The pivot stud 27 on the lever 26, 110 is carried by a slide 43, which is capable of adjustment horizontally by operating the screw 44. It will be evident that by shifting the pivot stud forwardly, a greater pressure is brought to bear on the roll 17, and by 115 shifting it in the opposite direction, the greater proportion of pressure is transmitted to the detaching roll.

The operation of the comber will be ap-
120 parent without further description. It will be noted that the detaching roll operates independently of the piecing rolls and is called upon to revolve only in a forward direction, taking its motion directly from the comb cylinder, while the piecing rolls 17 and 18 are driven from the drive-head on fixed axes. The motion they receive advances the detached tuft far enough to avoid contact of the needle half-lap with the tail end of 125 the tuft but to present or leave a sufficient 130

length of tail to form the overlap with the next detachment.

The supporting mechanism for the top comb 11 has not been shown or described because it may be made in any usual or suitable way. It will be understood, however, that it is set to operate as close as may be to the segment, being either fixed in this position or receiving an oscillating motion which brings it to its lowest point at the proper moment. The support for the nipper jaw or cushion plate 8, also omitted from the drawings, may likewise be provided in any suitable form. Preferably such jaw is held in about the position indicated, that is to say, somewhat in the rear of the vertical center of the comb cylinder.

I claim:

1. In a cotton comber, means for feeding and nipping the lap, a top comb and a comb cylinder, in combination with two adjacent rolls arranged in front of the top comb and both adapted to nip the tuft beneath them, such rolls having sleeve bearings on their gudgeons and means common to adjacent sleeves for imparting the nipping pressure to the said rolls.

2. In a cotton comber, lap-feeding and nipping means, a top comb and a comb-cylinder in combination with a detaching roll, and piecing means independent of such roll, said means comprising a roll in front of the detaching roll and means for weighting said two rolls comprising a saddle device spanning the end bearings thereof.

3. In a cotton comber, lap-feeding and nipping means, a top comb and a comb cylinder having a detaching segment, a detaching roll adapted to nip the tuft against the segment, a roll in front of the detaching roll between which and the detaching segment the tuft passes, saddles spanning the gudgeons of said rolls and means for weighting the said saddles.

4. In a cotton-comber having lap feeding and nipping means, and a comb cylinder with a detaching segment thereon, the combination of a detaching roll engaging the segment in front of the nipping means, a separate roll in front of the detaching roll and a third roll in front of the second, means for supporting the first and second rolls comprising slot bearings in which the gudgeons of the detaching roll are movable toward and from the rear of the comb cylinder, and bearing surfaces on which the gudgeons of the second roll are movable toward the third roll, a saddle member acting on adjacent gudgeons of both said rolls and stirrup members imparting pressure to the saddle members.

5. In a cotton comber the combination with the lap-feeding and nipping means, a comb cylinder having a detaching segment, and a detaching roll adapted to engage the

segment, of a pair of intermittently operating, piecing rolls in front of the detaching roll, one of which rolls is subject to pressure against the other, means for applying such pressure comprising a saddle one end 70 of which bears on the detaching roll and the other on the said piecing roll and a stirrup member bearing on the said saddle and imparting pressure thereto.

6. In a cotton comber the combination 75 with the lap-feeding and nipping means, a comb cylinder, and a set of rolls in front of such nipping means, means for weighting two of such rolls comprising a saddle acting on the adjacent ends thereof and a stirrup 80 member permanently joined to the saddle.

7. In a cotton comber, means for detaching and piecing the tufts comprising two weighted rolls, a saddle acting on adjacent gudgeons of said rolls and a weighting stirrup 85 to which the saddle is pivotally connected.

8. In a cotton comber, means for detaching and piecing the tufts comprising two weighted rolls, a saddle bearing with one 90 end on the end of one of said rolls and having a leg which bears upon the end of the other roll and a weighting stirrup joined to the saddle.

9. In a cotton comber, the combination 95 with the comb cylinder having a detaching segment, and lap-feeding and nipping means, of a detaching roll in front of the nipping means, a piecing roll in front of the detaching roll and a pair of weighting stirrups 100 having saddle means permanently connected thereto for applying the nipping pressure to both said rolls, the said stirrups being adapted to be removed from the rolls when removing the latter and having their 105 lower ends extended below said rolls.

10. In a cotton comber, the combination with the comb cylinder having a detaching segment, of a detaching roll, a second roll 110 in front of the detaching roll, both rolls having gudgeon sleeves, a weighting stirrup for both rolls having a saddle permanently connected therewith and applying nipping pressure to adjacent gudgeon sleeves thereof, the said stirrups and saddles being removable from the comber.

11. In a Heilmann type cotton comber, the combination with the lap-feeding and nipping means, of a comb cylinder having a segment, a detaching roll and piecing 120 rolls separate therefrom, of supporting and guiding means for the detaching roll and one of the piecing rolls consisting of a block the upper surface whereof supports the said piecing roll, a slot in said block to receive 125 the gudgeon of the detaching roll, and means for adjusting said gudgeon within the recess.

12. In a cotton comber having detaching and piecing rolls both having gudgeon 130

5 sleeves, one of which rolls coats with a detaching segment and the other with another piecing roll, means for applying nipping pressure to both said rolls comprising a stirrup member, and a saddle supporting the latter and set upon adjacent gudgeon sleeves of both rolls so that it spans the gudgeons thereof, and a weight lever engaged to the stirrup and imparting pressure therethrough

10 to the saddle.

13. In a cotton comber, lap-feeding and nipping means, a comb cylinder having a needle-half-lap, forwardly and rearwardly inclined bearing surfaces at the ends of the cylinder, a detaching roll mounted by its gudgeons on the rearwardly inclined surfaces, a second roll mounted by the gudgeons on the forwardly inclined surfaces, means for supporting the detaching roll

15 on its said bearing surfaces so that it escapes contact with the needle-half-lap and a common pressure means for both rolls including a saddle member spanning the gudgeons thereof and imparting nipping pressure to said rolls.

14. In a cotton comber, lap-feeding and nipping means, a comb cylinder having a detaching segment, a detaching roll co-operating therewith and having a boss by which it is driven, a second roll in front of the detaching roll and out of contact therewith, and a common means for weighting both said rolls, in combination with roll-driving members at the ends of said cylinder adapted to engage the said boss and rotate the detaching roll.

15. In a cotton comber, lap-feeding and nipping means, a comb cylinder, bracket arms at the ends of such cylinder having 40 forwardly and rearwardly inclined bearing surfaces, a detaching roll mounted by its gudgeons on the rearwardly inclined surfaces and a second roll mounted on the forwardly inclined surfaces, in combination with bosses on the ends of the detaching roll and driving bearings for such bosses at the ends of the cylinder, such bearings being adapted to support the detaching roll upon its said rearwardly inclined bearing

45 surfaces, and weighting means for said rolls arranged to press the detaching roll upon the said surfaces and the driving bearings.

16. In a cotton comber, the combination with a comb cylinder having a detaching segment, a detaching roll engaging intermittently therewith and provided with bosses having a diameter not exceeding the working surface of the roll, and driving surfaces concentric with the cylinder adapted to engage and rotate such bosses prior to the engagement of the roll with the detaching segment.

17. In a cotton comber, the combination of lap-feeding and nipping means, a comb cylinder having a detaching surface, a de-

taching roll engaging intermittently therewith and means for rotating the detaching roll prior to such engagement, in the same direction and at a higher surface speed.

18. In a cotton comber, a comb cylinder 70 having a needle half lap and a detaching segment radially higher on the cylinder than the points of the needles, in combination with a detaching roll having bosses fixed thereon, and bearing surfaces concentric 75 with the cylinder adapted to engage and rotate the bosses prior to the engagement of the high segment with the working surface of the detaching roll.

19. In a cotton comber, a comb cylinder, 80 having a detaching segment, a detaching roll engaged thereby, piecing rolls operating independently of the detaching roll and means for forwardly driving the detaching roll prior to and at the beginning of its 85 engagement by the segment.

20. In a cotton comber, the combination with a comb cylinder having a needle-half-lap and detaching segment, a detaching roll having end bosses whereby it is supported 90 and rotated prior to its engagement with the segment, ring bearings on the cylinder adapted to support and drive said bosses, said bearings being proportioned to support the working face of the roll above the needle 95 half-lap and below the detaching surface of the segment.

21. In a cotton comber, the combination of a comb cylinder having a needle-half-lap, a detaching roll, bearing members on the 100 cylinder adapted to support and rotate the detaching roll with its working surface above the needle points, a detaching segment on the comb cylinder adapted to engage the roll while supported on said bearing members, and a beveled surface on the segment 105 tending to raise the detaching roll by engagement therewith.

22. In a cotton comber, the combination of a comb cylinder having a detaching segment, an independent detaching roll engaged by the segment and means for piecing the tufts detached thereby, in combination with supporting means for the ends of the detaching roll comprising an arm having a slot therein, an adjustable bottom bearing in the slot, gudgeon sleeves on said roll confined in said slot and adapted to rest in said bottom bearings during the intervals 110 between engagement of the detaching roll 115 by the segment.

23. In a cotton comber, a comb cylinder having a detaching segment, a detaching roll having gudgeon sleeves and means for supporting the same comprising a bearing block 120 slotted to receive such sleeve and provided with a screw tapped within said block and slot and forming a bottom bearing for the sleeve in the slot.

24. In a cotton comber, a comb cylinder 125

having a detaching segment, a detaching roll provided with a gudgeon sleeve and means for supporting the roll comprising a slotted bearing block receiving the sleeve, a screw 5 tapped into the block and slot from the rear of the comber and forming a bearing for the sleeve.

25. In a cotton comber, the combination with a comb cylinder having a detaching 10 segment and a detaching roll having bosses at its ends by which it is driven, of roll driving means in the cylinder for engaging the bosses to start the detaching roll in motion prior to its engagement by the segment.

15 26. In a cotton comber, the combination with the detaching roll, of a stirrup member for transmitting pressure to such roll and means adapting such member to be shifted from engagement with the roll without re- 20 lieving the pressure on the stirrups.

27. In a cotton comber, a detaching roll, a 25 stirrup member subjected to pressure, a device receiving pressure from the stirrup and adapted to transmit it to the detaching roll, and a bearing for said device on which it may be turned to interrupt such transmission to the detaching roll.

28. In a cotton comber, a detaching roll,

and a stirrup subjected to pressure and arranged to transmit the same to the roll, in 30 combination with a device connected with the stirrup and having a bearing or support whereby forward pull on the stirrup relieves the roll from pressure.

29. In a cotton comber, the combination 35 with the comb cylinder, and two rolls adapted to coöperate to detach and piece the combed tufts, of a common means for transmitting nipping pressure to both such rolls and means for varying the proportion of 40 pressure transmitted to each.

30. In a cotton comber, the combination with the comb cylinder and two rolls adapted for operation on the combed tufts, of a 45 member spanning both rolls, a stirrup applying pressure to both such rolls through the said member and means for shifting the direction of pull of said stirrup.

In testimony whereof, I have signed this 50 specification in the presence of two witnesses.

GEORGE M. WHITIN.
